UNITED STATES PATENT OFFICE.

STEPHEN G. WRIGHT, OF OAK PARK, ILLINOIS.

ROOFING MATERIAL.

1,022,764.

Patented Apr. 9, 1912.

Application filed May 29, 1911. Serial No. 830,179.

To all whom it may concern:

Be it known that I, STEPHEN G. WRIGHT, a citizen of the United States, residing at Oak Park, in the county of Cook and State 5 of Illinois, have invented a new and useful Improvement in Roofing Material, of which the following is a specification.

My invention relates, more particularly, to improvement in prepared roofing of the 10 variety involving the use of a sheet of felt or other fibrous material forming the body of the roofing, saturated and coated with bitumen, coal-tar, or any other suitable organic or mineral wax; and my object, generally stated, is to provide such sheets of 15 roofing with a surface-layer of wear-resisting material formed of particles partially embedded in the coating thereon and of such material as to permit of the production 20 of roofing of a wide range of durable colors and shades, which shall be permanent or lasting notwithstanding wear of the layer.

The accompanying drawing shows, by a 25 view in perspective, a sheet of roofing material constructed in accordance with my invention.

In the manufacture of my improved roofing I employ, preferably, a sheet 2 of felt, or other fibrous material and treat it to a 30 hot bath of bitumen, coal-tar, or any other suitable organic or mineral wax, as is common practice, to impregnate the fibrous sheet and produce on the upper surface thereof a coating of such substance, as represented at 3. I then spread upon the coating 3, while it is hot, a layer of particles 4 and partially embed the same therein in any suitable manner, as by passing the sheets, thus coated, between rollers.

40 In carrying out my invention, I use for the surface coating, formed of the particles 4, masses of baked earthy materials, such as those materials of which brick, tile, pottery and the like are formed, reduced, as by 45 crushing, to preferably about 10 to 12 mesh, though the sizes of the particles 4 may vary, according to desire, from that stated. These particles thus become partially embedded in the coating 3, and are sufficiently close

50 together to cause the exposed surface of the roofing to present the color of the particles 4 as a substantially unbroken surface as to color. The particles of baked earthy materials, such as those herein enumerated, are 55 of a porous nature, and form a preservative coating over the bitumen, coal-tar, or other

water-proof material forming the base of the roofing sheet, as well as presenting a roofing surface of predetermined coloring and of a permanent color under wear.

By employing the particular material composed of the particles 4, as stated, for the surface coating of the roofing not only may a wide range of colored roofings be provided by mixing certain of the earthy materials together in different proportions and mixing other ingredients with such earthy materials, as well as varying the time during which they are exposed to the heat in the baking operation as is well understood in the arts relating to the manufacture of brick, tile, pottery and the like, but different shades of colors may be produced and surface-coatings for the roofing having not only uniform, but lastingly uniform, color may be provided.

In the use of the materials enumerated and prepared in the manner stated it is possible not only to produce roofing having a protecting coating of a wide range of 80 colors, but also to produce such coating of mottled or variegated coloring. Furthermore, by constructing roofing in accordance with my invention, not only may the exposed surface of the roofing present different or blending colors, and shades of color, but the surface-coatings thereof, by reason of the materials of which the particles 4 are formed, retain their original color indefinitely, as each particle is of homogeneous 85 color throughout, and the wearing away of these particles under the action of the elements has no effect in the way of impairing the preservation of the color originally presented by the roofing. Another advantage 90 due to the use of the material stated, in its preferred form, for the surface coating of the roofing is that of durability, in that such material, when crushed, presents not only an irregular fracture, but a roughened 100 surface due to its porosity, and thus a tenacious bond between the particles 4 and the coating 3 is produced when these particles are embedded therein.

What I claim as new, and desire to secure 105 by Letters Patent, is—

1. As a new article of manufacture, roofing composed of sheet water-proof material having its surface composed of comparatively coarse particles of baked earthy material of predetermined coloring whereby a 110 roofing surface is produced presenting a

coloring permanent under wear, for the purpose set forth.

2. As a new article of manufacture, roofing composed of sheet water-proof material having its surface composed of particles of baked earthy material of predetermined coloring, said particles being partially embedded in a waterproofing coating and ex-

tending above the plane thereof, whereby a roofing surface is produced presenting a coloring permanent under wear, for the purpose set forth.

STEPHEN G. WRIGHT.
